UNITED STATES PATENT OFFICE.

FRANK W. SMITH, OF PORTLAND, MAINE.

STERILIZING-RETORT.

SPECIFICATION forming part of Letters Patent No. 624,989, dated May 16, 1899.

Application filed July 23, 1898. Serial No. 686,652. (No model.)

To all whom it may concern:

Be it known that I, FRANK W. SMITH, a citizen of the United States, residing at Portland, in the county of Cumberland and State 5 of Maine, have invented certain new and useful Improvements in Sterilizing-Retorts; and I do hereby declare that the following is a full, clear, and exact description of the invention, which will enable others skilled in the art to 10 to which it appertains to make and use the same.

My invention relates to retorts by which meats, vegetables, and other foods and substances contained in hermetically-sealed vessels or other packages may be sterilized by 15 subjecting them to the action of steam or heat; and it consists in certain mechanism by which the vessels or packages may be rotated while subjected to the action of the steam or heat within the retort.

20 The invention embraces a box or cylinder having a door secured in the ordinary manner, so as to render the retort steam-tight, a car upon which the trays containing the cans are placed and which may be rolled into or 25 otherwise placed within the retort, and means in each tray whereby the cans resting thereon may be rotated by means applied from without the retort.

In the drawings, Figure 1 is a vertical section 30 of the retort and part of the car, the remainder of the car being shown in side elevation; Fig. 2, an end view of the retort; Fig. 3, a vertical transverse section of a tray; Fig. 4, a detail in part section of one end of a tray, 35 showing the mechanism for rotating the cans; Fig. 5, a horizontal section of part of the retort, showing part of a tray in top plan.

Referring to the drawings, *a* is the retort, *c* being the door.

40 *b* is the car, which is of the ordinary construction, provided with trucks in the usual manner and having the rear end open.

At the side of the rear end of the retort is placed a vertical shaft *d*, which at regular intervals is provided with worms *e*, and also has at the top a beveled gear *f*, which matches with the beveled gear *g* on the shaft *h*, which is placed upon the top of the retort and which at the opposite end is provided with a pulley 45 *i*. The sides of the car are provided within at equal intervals with ledges, the spaces between the respective ledges being substan-

tially coincident with the worms *e*. The trays *k* are of ordinary construction, but are provided at either end with shafts *l*, which 55 carry the sprocket-wheels *m*, connected by the endless chain *n*. (See Fig. 3.) Upon the top of the endless chain *n* are secured slats *p*. The sprocket-wheels should be so placed that the upper surface of the slats *p* when upon 60 the tops of the sprockets should be about upon a level with the top of the walls of the tray. The tops of the trays are provided, as seen in Fig. 4, at equal intervals with ears, in which, extending from side to side of the tray, are the 65 rods *r*, the intervals or spaces between the rods being slightly greater than the diameter of the cans to be treated. Upon the right-hand end of the shafts *l*, at the rear of the trays, are placed the gears *o*. 70

The operation of the device is as follows: The cans are placed between the rods *r*, as shown in Fig. 4, until the trays are completely filled. The trays are then run into the car *b* from the open end upon the ledges, the gears 75 *o* being all upon the same side and the wall of the car being slotted at the proper points to receive the shafts *l*, as shown in dotted lines in Fig. 1. When the car is full, it is then rolled into the retort through the door *c* until the 80 rear truck rests against the stop *s* upon the bottom of the retort, when the gears *o* will match with the worms *e* upon the shaft *d*. The forward wheels of the car are secured by the trig or stop *t* upon the floor of the retort. 85 The door *c* of the retort is now secured in position, the steam or heat admitted, and power applied to the pulley *i*, causing the worms *e* to rotate, thus revolving the gears *o*, which put in motion the endless chain *n*, which by friction upon the peripheries of the cans causes 90 them to revolve. In this manner the contents of the cans are kept in constant agitation while the cooking process goes on. When the contents of the cans have been sufficiently cooked, the doors are opened, the car 95 removed, and the cans taken from the car.

What I claim is—

In a retort for sterilizing food contained in cans or other cylindrical packages, the combination of a retort having a horizontal shaft with worms thereon, a car provided with trays, said trays having therein sprocket-wheels provided with an endless chain and 100

slats, gears outside said trays intermeshing with said worms and means upon the tops of the trays whereby one row of cans may be separated from those adjacent to it whereby
5 said cans are revolved on their own axes, substantially as described.

In testimony that I claim the foregoing as

my invention I have hereunto set my hand this 21st day of July, A. D. 1898.

FRANK W. SMITH.
